[57] CLAIM

The ornamental design for a shoe upper, as shown and described.

DESCRIPTION

FIG. 1 is a left side elevational view of a shoe upper showing our new design;
FIG. 2 is a right side elevational view thereof;
FIG. 3 is a top plan view thereof;
FIG. 4 is a front elevational view thereof;
FIG. 5 is a rear elevational view thereof;
The broken line showing of a shoe sole is environmental only and forms no part of the claimed design.

FIG. 1**FIG. 2**

FIG. 3

FIG. 4

FIG. 5
